UNITED STATES PATENT OFFICE.

JOHN E. BELL, OF BROOKLYN, NEW YORK, ASSIGNOR TO POWER SPECIALTY COMPANY, OF NEW YORK, N. Y., A CORPORATION OF NEW YORK.

SUPERHEATER.

1,409,651.

Specification of Letters Patent. Patented Mar. 14, 1922.

Application filed December 11, 1919. Serial No. 344,114.

To all whom it may concern:

Be it known that I, JOHN E. BELL, a citizen of the United States of America, residing at Brooklyn, in the county of Kings and

5 State of New York, have invented certain new and useful Improvements in Superheaters, of which the following is a full, clear, and exact description.

In the case of any of the usual types of 10 steam boilers, which are exemplified, for instance, in Babcock & Wilcox, Heine or Stirling boilers, the problem of superheating the steam, particularly under the prevailing demand for high pressure service 15 and high degrees of superheat, is one which has called upon steam engineers to expend much effort to comply with the commercial requirements. Primarily, of course, practical conditions necessitate the use of relatively 20 small heating surface, but this, when high temperatures or superheat are demanded, involves their protection from the hot gases to prevent their being burned out, and for this purpose the gases must be caused 25 to sweep more or less of the boiler heating surfaces before they are permitted to impinge upon the superheater. This provision is met in practically all forms of boiler and arrangements of superheaters now in use, 30 but the difficulty in practice is that too much of the boiler heating surface must generally be passed by the hot gases before they reach the superheater, or else the latter must be placed in an inconvenient position, 35 such as where their support would be difficult or the radiation losses would be unnecessarily large, or extra space outside of the boiler setting would be required. Other and many disadvantages result when practical 40 designs are attempted.

Recognizing the fact that the tempering of the furnace gases before they reach the superheater is a practical necessity and at the same time seeking to obtain a high degree 45 of superheat with a relatively small heating surface I have devised a novel arrangement for superheaters which is applicable to many forms of boiler and more particularly to the standard types above 50 mentioned. I accordingly place the superheater in the position where economical considerations of construction, convenience of maintenance and proximity to the furnace would naturally suggest, but protect it by 55 bringing the heating surface of the boiler

between it and the fire so that the said boiler heating surface serves as a protective shield which tempers the gases before they reach the superheater tubes.

This may be done in a variety of ways, 60 but preferably by placing the superheater back of the bridge wall beneath the boiler, and protecting it by altering the direction of the first row of boiler heating tubes and causing them to pass through horizontal 65 manifolds so disposed as to provide a set of horizontal parallel tubes immediately above the superheating surface.

The superheating surface I arrange in horizontal rows of tubes connected to manifolds in any proper manner, and to better meet the demands of practical use I divide the superheater tubes into two groups separated by a dividing or partition wall which constitutes a form of baffle. This wall is an 70 important feature since it affords a ready means of adjusting or regulating the amount of superheat by its control of the volume of gases which are caused to pass the superheater. In other words, if more superheat 75 is required this wall is built higher so that a greater amount of hot gases will be forced over the superheater. On the other hand if less superheat is needed the wall is built lower and the volume of deflected gases correspondingly diminished.

This invention requires certain specific details of construction and design for the accomplishment of the best results, but these will be hereinafter described in the following description in which reference is made to the accompanying drawings.

Fig. 1 is a vertical sectional view of a boiler of the Stirling type to which my improvement is applied.

Figs. 2 and 3 are sectional details of modified arrangements of the superheater tubes, and

Fig. 4 is a vertical sectional view of another type of boiler, that known as a Babcock & Wilcox, with the improvement applied thereto.

The boilers herein shown, except in the particulars noted, are of the usual form of construction known in the art, and are selected merely for showing the wide diversity of types to which the invention is applicable. In Figs. 1, 2 and 3 are the conventional upright banks of tubes connecting the lower drum 4, with the three upper

drums 5. The ordinary construction is, however, departed from by bending out the outside or front row of tubes 6, and connecting them to horizontal manifolds 7, which enter the lower drum and which form a horizontal screen over the superheater 8, mounted in a recess behind the bridge wall 9.

Back of the upright row of tubes 6 is a baffle 10, which extends partly up from the level of the bridge wall, and from the front upper drum 5 down to near the lower drum 4 is an extended baffle 11 between the second and the third row of upright tubes 15 of the first bank.

By this means the hot gases, as indicated by the arrows, pass upward from the furnace over the tubes 6, then downward between the baffles 10 and 11 sweeping the second row of tubes of the first bank and then upward, following the usual course in boilers of this type.

Associated with the superheater 8, whose tubes are horizontally disposed, is a baffle 12 which may be supported and constructed in any suitable manner, but which projects up into the path of the gases and diverts a certain proportion of them down over one part of the superheater tubes and up over the other. In this way any proportionate amount of the total volume of gases may be caused to sweep the superheater after they have swept the first row of boiler tubes 6 and passed through the horizontal manifolds 7. These gases may be still further tempered, if need be, by placing the baffle 11 back of the third or outer row of upright tubes of the first bank.

Referring to Fig. 4 as illustrative of a radically different type of boiler: Back of the bridge wall a suitable recess or chamber is provided for the superheater and over the latter are the horizontal manifolds 7 connected to the lowermost row of boiler pipes 6 at one end and to the rear boiler header 13 at the other. The tubes 6 are properly bent down for this purpose and above them or preferably above the second row of tubes a baffle 11 is placed that impedes to the flow of hot gases the directions indicated by the arrows.

In this figure the superheater tubes are shown as divided into two distinct groups 14 and 15 and the dividing partition or baffle 12 is carried up between the two groups, being cut away beneath them to afford a free passage for the gases.

One of the subordinate features of this invention which contribute to its success is well illustrated in this figure in connection with Figs. 2 and 3. The inlet pipe 16 from the boiler is connected to the middle of the superheater header 17, while the opening 18 from the outlet header 19 instead of being 65 at the middle is at the end of said header.

The position of these openings is worked out so as to produce compactness of design. It moreover insures an ideal distribution of steam throughout the superheater tubes and in a general direction counter to that of the 70 heating gases. Without increasing the length of the headers, it permits a staggered disposition of the superheater elements by which those in the upper row are placed directly above the spaces in the lower row, 75 and furthermore in such an arrangement as shown in Fig. 4, this staggering is oppositely arranged on the two sides of the baffle wall which tends to a better contact of the surface with the heating gases which 80 pass below the wall.

Another important feature of the improvement is due to the relatively small proportion of the high temperature gases which 85 sweep the superheater tubes. This is an element of safety when firing up the boiler and before steam begins to flow through the superheater. The limited amount of heat to which the superheater surface is exposed 90 is not sufficient, under these conditions, to burn out the superheater as might be the case were all the gases from the fire caused to pass over it.

Different arrangements of superheater tubes are possible and practicable. In Fig. 95 2 the two rows are connected in multiple to the headers, while in Fig. 3 they are in series. In either case the supports are all independent of the boiler and may be simply and economically designed.

The construction shown and described may be widely modified, as will now be evident, without departure from the invention.

What I claim is:

1. The combination, with a water tube 105 boiler of a superheater placed below but in proximity to the tubes of such boiler, and baffling which causes the hot gases to sweep the boiler tubes and diverts a portion of such gases from their normal path over the 110 superheater tubes, a portion of the boiler tubes being bent from their normal position to form a protective shield over which the said diverted gases pass before they 115 reach the superheater tubes.

2. The combination with a water tube 120 boiler of a superheater placed below but in proximity to the boiler tubes, and baffling causing the hot gases to sweep the boiler tubes and diverting a portion of such gases from their normal path causing the gases to sweep the superheater tubes, a portion of the boiler tubes being bent from their normal position and carried in a horizontal row over the superheater so that the said diverted gases must sweep such horizontal water tubes before reaching those of the superheater.

3. The combination in a water tube boiler 130 of a superheater placed below but in prox-

- imity to the water tubes, baffling causing the hot gases to sweep over the boiler tubes, and diverting a portion of said gases from their normal path over the boiler tubes and 5 causing the same to sweep over the superheater tubes, a portion of the boiler tubes from one end of the boiler being carried in a horizontal row over the superheater and manifolds to which said tubes and those 10 leading to the other end of the boiler are connected, said horizontal tubes forming a protective shield over which the said diverted gases pass before reaching the superheater.
- 15 4. The combination in a water tube boiler of a superheater placed below but in proximity to the water tubes, the outer row of boiler tubes or those nearest the fire being bent from their normal position and carried 20 over the superheater, a baffle for causing the gases to sweep over the said bent tubes, and a baffle between the boiler and the superheater for deflecting a portion of the 25 gases and causing the same after passing the water tubes over the superheater to sweep the tubes of the latter.
5. The combination with a water tube boiler of a superheater with horizontal tubes placed beneath the same, the outer row 30 of boiler tubes or those nearest the fire being bent from their normal position and carried over the superheater, of baffles for deflecting the gases from the boiler tubes and causing a portion of the same to impinge 35 upon the superheater, and a vertical baffle at the middle point of the superheater.
6. The combination with a water tube boiler, of a superheater with horizontal tubes placed beneath the same, the outer row 40 of boiler tubes, or those nearest the fire being bent from their normal position and
- carried over the superheater, of baffles for deflecting the gases from the boiler tubes and causing a portion of the same to impinge upon the superheater and a vertical baffle 45 passing through the center of the superheater and dividing its tubes into two groups through which a proportion of gas determined by the height of said baffle passes in opposite directions. 50
7. The combination with a water tube boiler of a superheater with horizontal tubes placed beneath the same and headers therefor, the outer row of boiler tubes or those nearest the fire being bent from their 55 normal position and carried over the superheater, baffling for directing the flow of gases over such bent tubes and to the superheater, a vertical baffle between the superheater tubes dividing them into two groups, a 60 steam pipe from the boiler connected to the middle of the superheater inlet header, and a steam pipe connected to the end of the superheater outlet header.
8. The combination with a water tube 65 boiler, of a superheater having horizontal tubes placed beneath the tubes of the boiler, a horizontal row of tubes connected in series with the outer row of said boiler tubes or those nearest the fire and placed immediately over said superheater, baffles for causing the hot gases to pass over said outer row of boiler tubes, and over the horizontal tubes connected therewith, and a vertical baffle for deflecting a proportion of the 70 gases downward and upward over the superheater tubes which is determined by the height of said baffle. 75

In testimony whereof I hereunto affix my signature.

JOHN E. BELL.
